UNITED STATES PATENT OFFICE.

FRANK L. GEORGE, OF LOS ANGELES, CALIFORNIA.

DAMPER FOR GRAND-PIANO ACTIONS.

1,353,643.

Specification of Letters Patent. Patented Sept. 21, 1920.

Application filed September 9, 1919. Serial No. 322,727.

To all whom it may concern:

Be it known that I, FRANK L. GEORGE, a citizen of the United States, residing at Los Angeles, in the county of Los Angeles and 5 State of California, have invented new and useful Improvements in Dampers for Grand-Piano Actions, of which the following is a specification.

My object is to make an improved damper 10 for grand pianos, and my invention consists of the novel features herein shown, described and claimed.

A very objectionable condition existing in the grand action for all time is the very un- 15 equal touch with which the pianist has to contend owing to the alternate weight put onto the key through the operation of the dampers. Under the present form of construction it is out of the question to keep the 20 weight of touch on the key equalized, owing to the constantly alternating movement of the damper on and off the key caused by the operation of the loud pedal up and down. The act of using the loud pedal moves the 25 entire damper action upward from off the rear end of the key thereby taking its weight entirely from the key; this damper action constitutes about one-third of the weight on the key, so that when it is removed by the 30 pedal the weight of touch is about one-third lighter, and owing to the constant movement of the loud pedal by the performer there is a constantly alternating touch between heavy and light causing a most disagreeable 35 sensation to the pianist.

My object is to overcome the objectionable features of the old construction.

Figure 1 is a fragmentary sectional detail showing an equalizing damper for grand 40 pianos embodying the principles of my invention, the parts being in their normal positions with the key at rest.

Fig. 2 is a view analogous to Fig. 1 and showing the action when the key is struck.

45 The key 1 normally rests upon the back rail key cloth 2. The wire 3 is in its usual position above the rear end of the key 1. The damper lever rail 4 is substantially in the usual position and the damper lever flange 5 is secured against the front face of the rail 4 and extends upwardly. The damper lever 6 is pivotally connected to the damper lever flange 5 by a pin 7 and is normally substantially horizontal and extends for- 50 wardly from the damper lever rail 4. A round extension 8 extends from the lower

face of the damper lever 6 about one-third of the distance from its forward end. The equalizer 9 is substantially straight. The extension 8 is bifurcated and the equalizer 9 60 has an ear 10 fitting in the bifurcation and connected by a pin 11 like a hinge. The forward end of the equalizer 9 has a felt 12 fitting upon the rear end of the key 1 and a similar felt 13 is secured to the rear end of 65 the equalizer 9. The damper rod 14 engages the felt 13.

The damper rod 14 has an extension rod 15 and the extension rod 15 is hingedly connected at its rear end by a pin 16 carried by 70 an attaching plate 17 secured to the supporting arm 18 by a screw 19. The supporting arm 18 extends forwardly from the lower side of the damper lever rail 4. The arm 18 has a seat 20 in the upper face of its 75 forward end and a felt 21 rests in the seat 20 and supports the damper rod 14 when in its normal position. The loud pedal rod 22 extends upwardly through the bottom of the piano and engages the damper rod 14, so 80 that when the loud pedal is operated the rod 22 is reciprocated upwardly against the damper rod 14 and raises the damper rod 14 from the seat 21 thereby raising the rear end of the equalizer 9 as shown in dotted lines. 85

The movable damper lever flange 23 is pivotally connected to the damper lever 6 by a pin 24. The lifter wire 25 extends upwardly from the damper lever flange 23 through a support 26, and the damper 27 90 is connected to the upper end of the lifter wire 25 in position to engage the piano wire 3.

A spring 28 has a forward end 29 bearing upon the damper lever 6 near its center, a 95 coil 30 near its rear end, and a rear end 31 bearing upon the rear end of the damper lever 6. The coil 30 forms a bearing and the wire is inserted through the bifurcation in the upper end of the damper lever flange 100 5 and a pin 32 is inserted through the damper lever flange 5 and through the coil 30.

When the loud pedal is operated by the performer the loud pedal rod 22 immediately actuates the damper rod 14, which in 105 turn raises the rear end of the equalizer 9 which having its forward end resting on the key 1 exerts its influence on the damper lever 6, which in turn lifts on the movable damper lever flange 23, which in its turn 110 carries upward the lifter wire 25 which raises the damper 27 from the piano wire

3 resulting in the final positioning of all parts as shown by dotted lines in Fig. 1; and during this operation the equalizer 9 has at all times retained an equal pressure 5 on the key 1, and the damper mechanism exerts an equal pressure upon the key at all times instead of being raised from the key by the operation of the loud pedal as in the old construction thus producing a touch 10 having a perfectly even resistance at all times.

Thus I have produced a damper for grand pianos comprising the combination with a damper lever, of an equalizer pivotally connected at its center to the free end of the damper lever, one end of the equalizer resting upon the rear end of a piano key and the other end of the equalizer resting upon the damper rod, so that when the loud pedal 15 is operated to raise the damper construction 20 the front end of the equalizer is always upon the piano key so as to make a uniform touch.

Various changes may be made without departing from the spirit of my invention as 25 claimed.

I claim:

1. A damper for grand pianos comprising the combination with a piano key and a damper lever, of an equalizer pivotally connected to the free end of the damper lever, one end of the equalizer resting upon the 30 rear end of the piano key and the other end of the equalizer resting upon the damper rod, so that when the loud pedal is operated 35 to raise the damper mechanism the forward end of the equalizer is always upon the piano key, thereby equalizing the touch.

2. In a damper for grand piano actions, in combination with a key, a damper lever 40 and a damper rod; an equalizing lever resting upon the inner end of the key and upon the rod, being connected intermediate of its

ends with the damper lever and forming a support therefor.

3. In a grand piano, the combination with 45 a key, a horizontally disposed damper lever and a damper rod; of an equalizing lever positioned to support the outer end of the damper lever; one end of said equalizing lever being in contact with the key and the 50 other end being in contact with the damper rod; said contact being maintained irrespective of the movement of the key or the damper rod.

4. In a damper for grand piano actions, 55 in combination, a damper lever pivotally mounted and having a lug extending from its lower side adjacent to its outer end, an equalizing lever having an upwardly extending lug pivotally connected with the lug 60 of the damper lever and a cushioning pad fixed to each end of the equalizing lever, the lever resting at one end upon a key and at the other end upon a damper rod.

5. In a grand piano, the combination with 65 a key, a loud pedal mechanism, a horizontally disposed damper lever and a damper rod; of means horizontally disposed under the damper lever for substantially equalizing the action touch of the key irrespective 70 of the movement of the damper rod, said means being operatively connected to said loud pedal mechanism and said key.

6. In a grand piano, the combination with 75 a key, a horizontally disposed damper lever and a damper rod; of means pivotally connected to the damper lever for substantially equalizing the action touch of the key irrespective 80 of the movement of the damper rod; said means being in permanent contact with the key and the damper rod.

In testimony whereof I have signed my name to this specification.

FRANK L. GEORGE.
